(57) **CLAIM**

The ornamental design for a collapsible golf trolley, as shown and described.

DESCRIPTION

FIG. 1 is a front upper right perspective view of the collapsible golf trolley of the present invention in an open condition;

FIG. 2 is a front upper left perspective view of the collapsible golf trolley of the present invention in an open condition;

FIG. 3 is a rear upper right perspective view of the collapsible golf trolley of the present invention in an open condition;

FIG. 4 is a rear upper left perspective view of the collapsible golf trolley of the present invention in an open condition;

FIG. 5 is a front elevational view of the collapsible golf trolley of the present invention in an open condition;

FIG. 6 is a rear elevational view of the collapsible golf trolley of the present invention in an open condition;

FIG. 7 is a right side elevational view of the collapsible golf trolley of the present invention in an open condition;

FIG. 8 is a left side elevational view of the collapsible golf trolley of the present invention in an open condition;

FIG. 9 is a top plan view of the collapsible golf trolley of the present invention in an open condition;

FIG. 10 is a bottom plan view of the collapsible golf trolley of the present invention in an open condition;

FIG. 11 is a front upper right perspective view of the collapsible golf trolley of the present invention in a folded condition;

FIG. 12 is a front upper left perspective view of the collapsible golf trolley of the present invention in a folded condition;

FIG. 13 is a rear upper right perspective view of the collapsible golf trolley of the present invention in a folded condition;

FIG. 14 is a rear upper left perspective view of the collapsible golf trolley of the present invention in a folded condition;

(Continued)

FIG. 15 is a front elevational view of the collapsible golf trolley of the present invention in a folded condition; FIG. 16 is a rear elevational view of the collapsible golf trolley of the present invention in a folded condition; FIG. 17 is a right side elevational view of the collapsible golf trolley of the present invention in a folded condition; FIG. 18 is a left side elevational view of the collapsible golf trolley of the present invention in a folded condition; FIG. 19 is a top plan view of the collapsible golf trolley of the present invention in a folded condition; and, FIG. 20 is a bottom plan view of the collapsible golf trolley of the present invention in a folded condition.
